UNITED STATES PATENT OFFICE.

WALTON HARRISON, OF NEW YORK, N. Y.

ART OF TRANSMITTING SOUNDS BY MEANS OF HERTZIAN WAVES.

1,122,594.

Specification of Letters Patent. Patented Dec. 29, 1914.

Application filed June 2, 1902. Serial No. 109,847.

To all whom it may concern:

Be it known that I, WALTON HARRISON, a citizen of the United States of America, and residing at New York, borough of Brooklyn, New York State, have invented 5 a new and useful Art of Transmitting Sounds by Means of Hertzian Waves, of which the following is a specification.

My invention relates to the art of transmitting sounds by means of Hertzian waves.

No particular type of mechanical device is essential to the practice of my art, but there are certain forms of apparatus which I prefer to use in connection therewith. In 15 the accompanying drawing, forming a part of this specification, and in which like letters indicate like parts, one such form is shown.

Figure 1 is a diagram, showing a wireless 20 transmitter, through the agency of which my art may be employed. Fig. 2 is a diagram of one form of wireless receiver which may be used in connection with the transmitter shown in Fig. 1.

25 A vibratory diaphragm (1), is mounted in the mouthpiece (2), and is highly polished. A lens (3), is so arranged so as to throw a strong light upon the diaphragm. Adjacent to the diaphragm is a conical reflector (4), preferably of metal, highly polished. Focused centrally within the reflector is a selenium rheostat (5), the terminals of which are the wires (6, 7), whereby the selenium rheostat is connected with a 35 battery (8), and also with the primary coil (9) of a transformer (10). The lens, diaphragm, reflector, selenium rheostat, battery and wires practically constitute a modification of Bell's photophone.

40 The secondary coil (11) of the transformer (10) is, by means of wires (12, 13), connected with an oscillator consisting of the polished knobs (14, 15), these knobs being connected respectively with the capacities (16, 17) by means of the wires (18, 19) and adjustably supported upon posts (20, 21). This oscillator is used in generating Hertzian waves in the usual manner, and is energized by the secondary coil (11).

45 The receiving instrument for detecting the Hertzian waves may employ an ordinary rotary coherer, such as is shown in Fig. 2. The coherer tube (22) is fitted with metallic disks (23, 24), which are connected with the rods (25, 26). The outer ends of these rods are enlarged and revolvably fitted into sta-

tionary metal cup-like bearings (27, 28). The metallic wings (29, 30), are connected with rods (31, 32), upon which the bearings are supported. The rods (31, 32) are 50 by means of wires (33, 34) connected with the impedance coils (35, 36), the battery (37) and the telephonic receiver (38). The space between the disks (23, 24) is partially filled with metallic filings (39) and the 55 coherer tube is rotated by gearing (40) for the purpose of decohering the filings, in the manner usual with rotary coherers. Any other suitable form of Hertzian wave detector may be used instead of the apparatus 60 shown in Fig. 2.

The operation of the mechanism shown in Figs. 1 and 2 is as follows: Ordinary light rays pass through the lens (3) and are concentrated upon the diaphragm (1), from 75 which they are reflected upward; striking the internal surface of the conical reflector (4), the rays are focused upon the selenium rheostat. Normally the selenium rheostat has great electrical resistance, but when 80 illuminated its resistance is lowered, as in Bell's photophone. If, now, sounds are produced adjacent to the mouthpiece (2), thus causing the diaphragm (1) to vibrate, the quantity of light entering the reflector 85 and concentrated upon the rheostat is varied with each vibration of the diaphragm, so that the electrical resistance of the battery circuit through the primary coil (10) is varied accordingly and the primary coil is 90 therefore energized by virtually intermittent currents of short duration. These currents are in many respects quite analogous to sound waves. The virtually intermittent currents passing through the primary coil, 95 of course induce intermittent but more powerful currents through the secondary coil (11). These induced currents are, of course, alternating in direction as is the case with induced currents now universally employed 100 in ordinary Bell telephones, but are far more powerful according to the strength of battery (8). They surge back and forth from one of the capacities to the other across the air gap between the knobs, propagating 105 Hertzian waves. The Hertzian waves pass through space and strike the wings of the coherer, varying the resistance of the filings (39) and thereby varying the current flowing from the battery (37) through the receiver (38), causing the same to emit sounds. 110 The rotation of the coherer tube (22) causes

the filings to decohere and the impedance coils (35, 36) are used as in a manner heretofore known in wireless telegraphy.

The selenium cell, under the influence of sound-controlled flashes of light and energized by a battery of several volts at least, is capable of handling comparatively heavy currents, and of producing rapid and substantial variations in the power thereof. In effect, therefore, it constitutes a very efficient form of interrupter, capable of inducing powerful spark discharges analogous to those of a Ruhmkorff coil. It follows, as a necessary consequence, that ordinary sounds such as that of the voice, may thus directly control the production of Hertzian waves, and that these waves, thus produced, have impressed upon them a certain arbitrary, undulatory character, analogous to that of sound waves; and that they vary in strength and character according to the strength and character of the sounds whereby they are controlled. The oscillatory character of the spark need not be brought into the discussion, because, owing to the high frequency of the oscillations, their individual effect is not perceptible.

The coherer is exceedingly sensitive when used in connection with a telephonic receiver and a delicate battery for the purpose of detecting slight variations in the strength and character of Hertzian waves, and the matter of sudden decoherence is of less importance in wireless telephony than in wireless telegraphy. The reason, I suppose, is that when the filings cohere, they are necessarily subjected to more or less mechanical or molecular stress, and therefore, owing to their elasticity, have a slight tendency to decohere automatically. After being affected by each Hertzian wave, therefore, they tend individually to resume their normal shapes. The slight decoherence thus automatically produced, while perhaps useful for wireless telegraphy, is sufficient to affect the telephonic receiver. According to Ganot, the variations of an electric current necessary to produce the audible noises in the telephonic receiver, may be of the order of hundred thousandths of an ampere. The effect is improved, however, by mechanical decoherence due to rotation. Within certain very narrow limits, the coherer responds quantitatively to the waves.

The expression "Hertzian waves" is herein used in its broad sense, including not only the electro-magnetic phenomena discussed by the late Heinrich Hertz, but all modifications thereof used in wireless telegraphy, whether aerial, subterranean or submarine.

Claims:

1. The art, herein described, of transmitting sounds by means of Hertzian waves; which consists in sending an electric current through a substance, the electrical con-

ductivity of which is influenced by light, exposing said substance to the action of light, causing sound waves to intermittently vary the quantity of said light to which said substance is exposed, causing said electric current to control the production of Hertzian waves, and causing said waves to control the production of distant sounds. 70

2. The art, herein described, of transmitting sounds by means of Hertzian waves; which consists in sending an electric current through a substance, the electrical conductivity of which is influenced by light, exposing said substance to the action of light, causing sound waves to intermittently vary the quantity of said light to which said substance is exposed, energizing a primary circuit by means of said electric current, causing the secondary circuit to induce an oscillatory static discharge, thereby propagating Hertzian waves, and causing said Hertzian waves to control the production of sounds at a distance. 80

3. The art, herein described, of transmitting sounds by means of Hertzian waves; which consists in sending an electric current through selenium, subjecting said selenium to varying quantities of light for the purpose of modifying said current thus passing through the same, causing the current thus modified to control the propagation of Hertzian waves correspondingly modified, and causing said waves, thus modified, to control the production of sound waves at a distance. 90

4. The art, herein described, of transmitting sounds by means of Hertzian waves; which consists in sending an electric current through a substance the electrical resistance of which is influenced by light, subjecting said substance to the action of varying quantities of light for the purpose of modifying said current, causing said current thus modified to energize a primary circuit, causing said primary circuit to energize a secondary circuit, thereby producing Hertzian waves, and causing said waves to control the production of sounds at a distance. 10

5. The art, herein described, of transmitting sounds by means of Hertzian waves; which consists in producing an electric current, causing ordinary light to vary the strength thereof, next producing mechanical sound vibrations, causing the same to modify the effect of said light upon said current, thereby producing variations analogous to sound waves in the flow of said current, then causing said current to induce a static discharge, next generating Hertzian waves by aid of said discharge, and finally causing said Hertzian waves to control the production, at a distance, of sounds simulating those first produced. 11

6. The art, herein described, of transmit-

ting sounds by means of Hertzian waves; which consists in producing sounds, causing the same to govern the production of intermittent flashes of light analogous to sound waves, causing said flashes of light to intermittently vary the normal strength of an electric current, causing said current, thus affected, to induce electrical surges in a separate circuit, thereby propagating Hertzian waves having impressed upon them an arbitrary undulatory character independent of the oscillatory character thereof, and causing said Hertzian waves, thus impressed, to control the production of sound vibrations similar to those first produced.

7. The art, herein described, of transmitting sounds by means of Hertzian waves; which consists in producing sound-controlled intermittent flashes of light, causing the same to virtually interrupt the flow of a current in a primary circuit, causing said current to induce electrostatic surges in a secondary circuit, thereby propagating Hertzian waves, and causing said Hertzian waves to control the production of distant sounds.

8. The art, herein described, of transmitting sounds by means of Hertzian waves; which consists in causing an electric current to pass through a medium offering thereto a variable resistance controllable by light, subjecting the same to the action of light, causing sounds to control the distribution of light affecting said medium, causing said electric current to induce a secondary current capable of generating Hertzian waves, and causing said Hertzian waves to control the production of sounds at a distance.

9. The art, herein described, of transmitting sounds by means of Hertzian waves; which consists in shedding light upon a medium having an electrical conductivity controllable thereby, causing sounds to control the quantity of light thus affecting said conductivity, passing a primary current through said medium, causing said current, while passing through said medium, to act inductively upon a circuit capable of generating Hertzian waves, and causing the Hertzian waves from said circuit to control the production of sounds at a distance.

10. The art herein described of transmitting sounds by means of Hertzian waves; which consists in causing said sounds to control the angular direction of light waves, causing said light waves to vary the electrical conductivity of a medium sensitive thereto, causing an electric current to flow through said medium and to have its energy controlled thereby, causing said electric current to produce other electric currents by induction and causing said other electric currents to produce oscillatory discharges across a spark gap thereby generating Hertzian waves impressed with undulations analogous to said sound waves, causing said Hertzian waves to travel to a distance and affect the resistance of an electric circuit, and causing said electric circuit to control the production of sound waves.

11. The art, herein described, of transmitting sounds by means of electromagnetic waves, which consists in generating electromagnetic waves by aid of two interdependent circuits, one of which is controllable by sound waves and is provided with a portion sensitive to light, the other being adapted to radiate said waves, and causing said waves to control the production of sounds at a distance.

12. The art, herein described, of transmitting sounds by means of electromagnetic waves, which consists in generating electromagnetic waves by aid of two interdependent circuits, one of which is inductively dependent upon the other, one of said circuits being controllable by sound waves and provided with a portion sensitive to light, the other being provided with a gap across which electricity flows incidental to the formation of said electromagnetic waves, and causing said waves to control the production of sounds at a distance.

In testimony whereof, I have signed my name to this specification in the presence of two subscribing witnesses, this 31st day of May 1902.

WALTON HARRISON.
